UNITED STATES PATENT OFFICE.

WILLIAM WHELAN, OF ST. JOSEPH, MISSOURI.

ELECTRICAL HEATING SYSTEM.

1,329,488.

Specification of Letters Patent.

Patented Feb. 3, 1920.

Application filed August 17, 1918. Serial No. 250,357.

To all whom it may concern:

Be it known that I, WILLIAM WHELAN, a citizen of the United States, residing in the city of St. Joseph and State of Missouri, have invented new and useful Improvements 5 in Electrical Heating Systems, of which the following is a specification, reference being had to the accompanying drawings.

This invention pertains to electrical heating devices, and to devices of this character especially adapted for heating water in boilers for the purpose of supplying steam or hot water for heating houses and for like purposes, and is an amplification of my invention on electrical heaters filed June 27, 15 1918, Serial Number 242,143.

This invention has for its object the production of an apparatus for this general purpose embodying the fewest possible parts 20 and with same assembled in a simple, practical and efficient form.

With these objects in view, attention is called to the accompanying drawings, wherein—

25 Figure 1 is a general perspective of a heating system properly constructed and assembled according to my invention, and showing the lay-out of the system as applied to a house, a boiler being located in the basement;

30 Fig. 2 is a modified form of construction showing the electrical heating elements attached to individual radiators in their respective rooms, the basement boiler being done away with;

35 Fig. 3 is an elevation of the parts and lay-out shown in Fig. 1;

40 Fig. 4 is a plan view of the lay-out projected upon the bottom plane;

45 Fig. 5 is a front elevation of the parts and lay-out as shown in Fig. 1;

Fig. 6 is a detail of the expansion tank with motor mounted thereon, and showing the electrical terminals and knife switch;

50 Fig. 7 is a detail showing the method of mounting the electrical heaters within the boiler or radiator.

Fig. 8 is a detail showing the method of insulating the boiler upon its exterior surface;

55 Fig. 9 is a detail showing the structure and formation of the individual heating cylinders;

Fig. 10 is a modification showing a flat 60 form of wick instead of cylindrical, said

wick being sandwiched between two perforated metal plates.

Referring more particularly to the drawings, my invention in its preferred construction, is made up primarily of a plurality of 60 heating units 25, each unit comprising two heating cylinders as 1 and 2 of unequal diameters, so that the heating cylinder 1 will set inside of the heating cylinder 2. These heating cylinders are both perforated with a 65 plurality of holes as shown at 3 and 4. A cylindrical asbestos wick 5 is disposed between the cylinders 1 and 2, and projects, as shown at 6 and 7, at its upper and lower ends beyond the ends of the heating cylinders 70 1 and 2. These heating units are mounted within the boiler 26 in such position that the lower ends 7 of the asbestos wick 5 extend toward the bottom of the boiler. The heating units 25 are supported 75 in position in the boiler 26 by suitable brackets 27. Suitable electrical conductors as 8 and 9 are joined to the heating cylinders 1 and 2, and lead therefrom upwardly through the top of the boiler 26, ending in 80 the terminals 11 and 12, and being insulated in passage through the top of the boiler by any suitable means. Wire conductors extend from the terminals 11 and 12, and are joined in circuit with any electrical source 85 as 16.

In the modification shown in Fig. 10, a flat form of structure is shown. The heating plates 20 and 21 are made flat, and between them is imposed the flat asbestos wick 90 22, these elements being clamped together in flat form by means of the clamps 23 and 24 bolted together at their ends. This structure so formed constitutes a heating unit in the flat form corresponding to the cylindrical 95 form shown at 25.

The boiler 26 is mounted upon a suitable cement base and is covered with an exterior insulation 29. In the top is mounted the safety valve 30 and the temperature gage 31. 100 On the side is mounted a water gage 32 and steam gage 33. A filling pipe 34 enters the top of the boiler and a drain pipe 35 pierces the lower part of the boiler. An expansion tank 36 is located at a suitable point relative 105 to the boiler 26 and is connected with the boiler 26 by the pipe 37. Upon the top of the expansion tank 36 is mounted the pressure motor 38, having a plunger 39 playing into the piston 40. The plunger 39 is con- 110

- nected to a horizontal lever 41, the inner end being supported from the bracket 42, and the outer end carrying the weight 43. Upon this lever 41 is mounted the knife switch 44. 5 Electrical terminals 45 and 46 are mounted adjacent to the said pressure motor in such position that the knife switch 44 will normally fall between and close said terminals. The pressure motor may be set at any required pressure represented in pounds. 10 Suitable electrical conductors as 47 and 48 extend from the terminals 45 and 46 and are placed in circuit with the aforesaid electrical conductors 8 and 9. Suitable hot 15 water or steam pipes and return pipes 49 and 50 extend from the boiler to the radiator 51.

In operation, the boiler or radiator is partially filled with water. The electric current is turned on, and water being only a 20 partial conductor of electricity, the resulting resistance from the current in passing between the heating cylinders 1 and 2, heats said cylinders, whereby the surrounding 25 water is heated, and a circulating current is established until the entire body of water is heated.

As the water is heated, or as steam is generated in the boiler, and the same passes to 30 the radiators in the rooms, the rooms become heated. As the pressure in the boiler increases, said pressure is conveyed to the pressure motor 38, and overcoming the pressure pounds at which same is set, the knife 35 switch 44 is raised, thereby opening the electrical circuit and cutting off the current from the heating cylinders 1 and 2, thus stopping a further heating of the water in the boiler 26. As the temperature falls 40 again, the pressure in the tank 36 diminishes, permitting the knife switch 44 to again lower and connect the terminals 45 and 46, thereby reestablishing the current.

If it should happen that all the water in 45 the boiler 26 should become converted into steam, the asbestos wicks 5, acting as insulators, would automatically open the electric current until the steam, becoming condensed, should flow back into the boiler, and as 50 water again close the electric current flowing between the cylinders 1 and 2.

While I have herein described a certain specific manner and method of constructing the elements of my invention, it is understood 55 that I may vary from the same in minor details, not departing from the spirit of my invention, so as best to construct a practical device for the purpose intended, as defined in the appended claims.

- 60 What I claim to be new and patentable is:
1. An electrical heating system, compris-

ing a source of electricity; a boiler and connected radiators; electrical heating units located within the boiler and in circuit with said source of electricity, said units being 65 composed of alternately disposed heating plates and absorbent, electrically non-conducting material; an expansion tank connected to said boiler; a pressure motor mounted on said expansion tank and adapted to respond to the varying pressure in the tank for the purpose of opening and closing the electrical circuit aforesaid.

2. An electrical heating system, comprising 75 a source of electricity; a boiler and connected radiators; electrical heating units located within the boiler and in circuit with said source of electricity, said units being composed of alternately disposed heating plates and absorbent, electrically non-conducting material; an expansion tank connected to said boiler; and means responsive to the varying pressure in the expansion tank for opening and closing the electrical circuit aforesaid.

3. An electrical heating system, comprising 80 a source of electricity; a boiler and connected radiators; electrical heating units located within the boiler and in circuit with said source of electricity, said units being 85 composed of alternately disposed heating plates and absorbent, electrically non-conducting material; an expansion tank connected to said boiler; a thermostat mounted on the expansion tank; electrical conductors 90 extending from the expansion tank and placed in circuit with the source of electricity and heating units aforesaid; and a switch operable by said thermostat for opening and closing said electrical circuit.

4. An electrical heating system, comprising 95 a source of electricity; a boiler with inlets, drains, gages and valves attached; radiators suitably connected with said boiler by 100 pipes; a plurality of electrical heating units located within the boiler and in circuit with said source of electricity, said units being composed of alternately disposed heating plates and absorbent, electrically non-conducting material; an expansion tank connected to said boiler; a thermostat mounted on the expansion tank; electrical conductors 105 extending from the expansion tank and placed in circuit with the source of electricity and heating units aforesaid; and a switch operable by said thermostat for opening and closing said electrical circuit.

WILLIAM WHELAN.
